UNITED STATES PATENT OFFICE

WILLIAM F. HUNT, OF NEW BRIGHTON, AND HERMANN C. STELLING, OF ORANGEBURGH, NEW YORK, ASSIGNEES TO UNION CARBIDE SALES COMPANY, A CORPORATION OF WEST VIRGINIA

ACETYLENE GENERATOR AND LAMP

Application filed September 14, 1927. Serial No. 219,533.

This invention relates to acetylene lamps and to generators of the type which may be used where a small portable generator is required and especially to improved means 5 for feeding water to the carbide.

An object of our invention is to provide an acetylene generator in which the water is fed to the carbide and in which the water feeding means is non-clogging, is provided 10 with a positive closure, and operates automatically to cut off the supply of water to the carbide when the carbide chamber is removed from the water chamber.

These and other objects of our invention 15 will be apparent from the following specification having reference to the accompanying drawing in which the single figure is a cross-sectional view of a combined generator and portable light constructed in accordance 20 with our invention.

In the drawing the generator G comprises a water chamber W and a carbide chamber C, the carbide chamber being cup-shaped and secured gas-tight to the water chamber by 25 any suitable means, as by a threaded collar 10 and a washer 11. A lamp housing L is secured to the removable cover W' of the water chamber by any suitable means. The bottom 13 of the water chamber is made 30 slightly conical in order that all the water may be available for use and about its center there is an annular depression 14 which serves to collect particles of dirt or foreign matter which might otherwise clog the water- 35 feed mechanism. A funnel shaped opening 15 provided with a cover 16 serves as a means for filling the water chamber.

A water passage connects the water chamber with the carbide chamber and is formed 40 by a tube 16 which extends downwardly from an opening within and above the bottom of the annular depression 14, the upper part of the tube being bevelled at 17 to form a valve seat. A rod 18 is loosely disposed in 45 and extends through the tube 16, being slightly smaller than the inside of the tube 16 so that the water may pass slowly between the rod and the tube. The upper part of the rod is enlarged at 19 to increase its weight and 50 thus form an inertia member. A protective

member 21 surrounds the tube 16. This member may be a spring, a wire screen or a perforated metal cylinder, as shown, and serves to keep the carbide from actual contact with the tube 16 thus diffusing the water into the 55 carbide in the chamber C. The lower end of the inertia member is bevelled to coact with the valve seat 17 for a purpose to be hereinafter described. A screw 22 is provided in the carbide chamber directly below the rod 60 18 and also fits into the lower end of the cylinder 21 to center the latter. This screw may engage directly with a threaded opening in the bottom of the carbide chamber but we prefer to employ an intermediate member 65 23 as shown. A washer 20 is provided between the head of the screw 22 and member 23. Suitable means are provided for conducting the gas from the chamber C to a burner 24 within the lamp housing L. While 70 various gas conducting means may be used, we have found that described and claimed in the copending application of Hermann C. Stelling, Ser. No. 217,393, filed September 3, 1927, well suited for this purpose. This 75 means, as shown, consists of a hollow boss 25 in the bottom of the water chamber and a tube 26 leading from this boss to a stabilizing chamber 27 on the top of the water chamber. The hollow boss contains a scrubber or filter 80 28 of felt, mineral wool or other suitable material, and the stabilizing chamber contains a disc 29 of filter stone or other pervious material for the purpose of controlling the flow of gas by reducing fluctuations in the pressure of the gas delivered to the burner 24, which is carried by the cover of the stabilizing chamber substantially centrally of the top of the water chamber and coaxial with the water feeding mechanism in the generator. 85

The operation of our device is as follows:

In normal operation the screw 22 raises the rod 18 sufficiently so that the valve formed by the tapered lower end of the inertia member 95 19 is clear of the valve seat 17. The water within the chamber W slowly passes down between the rod 18 and the inside of the tube 16 by capillary action or otherwise, thence through protective member 21 to the 100

carbide. Since the rod 18 is free to move both vertically and laterally in the tube 16, the movement of the lamp when carried or any vibrations when moving it will automatically cause a relative movement between the rod 18 and the inside of the tube 16, the inertia member 19 tending to accentuate these relative movements. This constant movement of the rod 18 will cause any foreign particles which are not collected in the depression 14 to pass down through the narrow space between the rod 18 and the tube 16. When it is desired to shut off or diminish the flow of water, the screw 22 is screwed upwardly so that the upper end of the screw engages or is close to the lower end of the tube 16, thus either cutting off or regulating the supply of water to the carbide chamber C, as desired. When it is desired to remove the carbide chamber from the water chamber, the former is rotated, disengaging the carbide chamber from the collar 10. As the carbide chamber is unscrewed, the weighted rod 18 moves downwardly and the beveled part of the inertia member 19 engages the valve seat 17, automatically cutting off the feed of water through the tube 16. It is, of course, evident that the water supply to the carbide chamber C may also be cut off or regulated by moving the screw 22 downwardly instead of upwardly. The taper on the inertia member 19 then engages the valve seat 17 in the same manner that it does when the carbide chamber is removed. However, when the supply is to be cut off for any considerable time this method should not be used as vibrations would permit a slight seepage of water into the carbide chamber.

From the foregoing it will be evident that our improved generator and lamp has numerous advantageous features. By arranging the control of the water feed at the bottom of the generator we are able to mount the lamp housing and the burner on the top of the generator. By a simple manipulation, the flow of water to the carbide chamber may be regulated as desired, or positively shut off; and the water feed mechanism operates automatically to shut off the water when the carbide chamber is uncoupled from the water chamber, as when recharging with carbide. Furthermore, the water feed mechanism is so constructed that the water feed passage is automatically freed from foreign particles which might interfere with the proper flow of water to the carbide chamber.

We claim:

1. A portable acetylene lamp comprising the combination of a water chamber having a cover; a carbide chamber below and coupled coaxially to said water chamber; mechanism for feeding water from the water chamber to the carbide chamber comprising a water passage connecting said chambers and coaxial therewith, and means control-

ling the flow of water through said passage including manually adjustable means extending centrally through the bottom of said carbide generator and operable to regulate or shut off the flow of water; a burner on said cover substantially coaxial with such feeding mechanism; and a housing on said cover for said burner.

2. A portable acetylene generator comprising the combination of a water chamber; a carbide chamber coaxial with and below said water chamber; a tube providing a water passage from the water chamber to the carbide chamber and having a valve seat at its inlet end; a rod extending through said tube and loosely disposed therein so as to be laterally and longitudinally movable relatively thereto, an enlargement on said rod in said water chamber, the lower end of said enlargement providing a valve cooperating with said valve seat, said enlargement constituting weight means tending to seat said valve and also intensifying lateral movements of said rod; and means operable to move said rod longitudinally to unseat said valve and also cooperative with the outlet end of said tube to regulate or shut off the flow of water through the latter.

3. A portable acetylene generator comprising a water chamber, a carbide chamber disposed below said water chamber, a tube extending downwardly from the bottom of said water chamber, a valve seat adjacent the junction of said tube and the bottom of said water chamber, a rod movable radially and longitudinally in said tube, an inertia member at the upper part of said rod, the bottom of said inertia member being adapted to engage with said valve seat and means carried by said carbide chamber for raising said inertia member from said seat, said means being also adapted to engage the bottom of said tube to close the same.

4. A portable acetylene generator comprising a water chamber, a carbide chamber disposed below said water chamber and movable for disengagement from said water chamber, a tube extending downwardly from the bottom of said water chamber, a rod movable radially and longitudinally in said tube, said rod being provided with an enlarged portion for engagement with the bottom of said water chamber and adjustable means on said carbide chamber for raising the enlarged portion of said rod out of engagement with bottom of the water chamber when said carbide chamber is in position, said means being further adjustable to engage the bottom of the tube to close the same.

5. An acetylene generator comprising the combination of a water chamber; a carbide chamber below said water chamber; a partition between said carbide chamber and said water chamber; means for feeding water

from the water chamber to the carbide chamber mounted on said partition, said feeding means comprising a tube extending downwardly from said partition and a rod loosely fitting said tube and provided with an enlargement for engagement with said partition; and adjusting means extending through the bottom of said carbide chamber for raising said rod.

6. A device as claimed in claim 5 in which the water feeding means includes means for urging the rod downwardly.

7. A device as claimed in claim 5 in which the enlargement on said rod serves as an inertia member to move the rod when said generator is subjected to jars incident to handling and transporting the same.

8. An acetylene generator comprising the combination of a water chamber; a carbide chamber below said water chamber; means including a water passage substantially coaxial with said generator and terminating adjacent the bottom of said carbide chamber, for feeding water from the water chamber to the carbide chamber; and means for controlling the flow of water through said passage, said controlling means comprising a rod in said passage, a valve carried by said rod constantly tending to close the inlet to said passage, and a screw extending through the bottom of said carbide chamber and manually adjustable from the outside thereof to operate said rod and valve and also adjustable relatively to the outlet of said passage to regulate or shut off the flow of water into said carbide chamber.

In testimony whereof, we affix our signatures.

WILLIAM F. HUNT.
HERMANN C. STELLING.
